FRANK CONRAD, OF SWISSVALE, PENNSYLVANIA, ASSIGNOR TO WESTINGHOUSE ELECTRIC AND MANUFACTURING COMPANY, A CORPORATION OF PENNSYLVANIA.

VEHICLE-LIGHTING SYSTEM.

1,171,595.

Specification of Letters Patent. Patented Feb. 15, 1916.

Application filed January 10, 1912. Serial No. 670,522.

To all whom it may concern:

Be it known that I, FRANK CONRAD, a citizen of the United States, and a resident of Swissvale, in the county of Allegheny and State of Pennsylvania, have invented a new and useful Improvement in Vehicle-Lighting Systems, of which the following is a specification.

My invention relates to systems of electrical distribution, and particularly to such systems as are employed upon automobiles and similar motor-driven vehicles for supplying current for lighting and other purposes.

15 The object of my invention is to provide such an arrangement of the connections of the lamps on the vehicle as to insure that their normal period of service shall not be diminished by the application of an excessive voltage to any of them.

Automobile and similar vehicles are ordinarily provided with head, side and tail lights, the head lights usually being of greater candle power than the others, so 25 that, when electric lamps are employed, the head lights take a greater amount of current than the others. On account of the comparatively large amount of current taken by the head lights, there is no danger 30 of applying an excessive voltage thereto, irrespective of the speed of the generator or the degree of charge of the battery, because the said current causes a suitable drop 35 of potential in the circuits of the system. However, when only the side and tail lights are in use, the voltage of the system may be in excess of the normal voltage of the lamps, particularly, when the battery is 40 fully or nearly charged, and the smaller amount of current taken by the said lamps will be insufficient to cause a material drop 45 of potential in the system, with the result that an undue voltage may be applied to the lamps, thereby shortening their useful lives. In the present instance, a resistance is connected in series with the side and tail lights for the purpose of preventing the application of an undue voltage thereto.

In the single figure of the accompanying drawing, which illustrates diagrammatically a system embodying my invention, a generator, the armature 1 of which is adapt-

ed to be driven by the vehicle engine, or by any other suitable means, is provided with a shunt field magnet winding 2 and a series 55 field magnet winding 3, the series winding opposing the shunt winding when the generator voltage exceeds a predetermined value. The generator is also provided with a centrifugal switch 4 that is adapted to 60 complete its armature circuit only when the armature is rotated at greater than a predetermined speed, which speed is such that the generator may produce substantially its 65 normal voltage. The generator supplies 70 current to a storage battery 5 through the series field magnet winding 3, and also to a distributing circuit comprising conductors 6—7, the series field magnet winding 3, however, being excluded from the connections 75 between the distributing circuit and the generator.

Current may be taken from the distributing circuit conductors 6—7 for any suitable purpose, but, as here shown, only the vehicle lights comprising head lights 8, side lights 9 and a tail light 10, are adapted to be supplied therefrom. The head lights are preferably of larger candle power than the side lights and the tail light, and in practice may be lamps of 16 candle power, while the side and tail lights may be lamps of 4 candle power. In order to connect the lights to the distributing circuit conductors, two snap switches 11 and 12 are provided, the switch 11 serving to connect only the side lights and the tail light to the said conductors, and the switch 12 serving to connect only the head lights and the tail light to the said conductor. The switch 11 is connected to the conductor 6 through a resistor 13 that is included in circuit with the side and tail lights when the switch 11 is closed, the purpose of the resistance being to slightly reduce the voltage of the distributing circuit 6—7 so that there may be no danger of applying an excessive voltage to the said lights, since the current taken by the said lamps, on account of their low candle power, is so small as to produce but a 95 comparatively small drop of potential in the system. This resistance is particularly useful when the battery is fully charged or nearly so, and the generator is operated at 100

full speed, since, under which conditions, the voltage of the distributing circuit may be somewhat above its normal value. No resistance is included in circuit with the 5 head lights for the reason that they require a comparatively large amount of current on account of their comparatively high candle power, this larger amount of current serving to reduce the potential of the distributing circuit so that an excessive voltage is 10 not applied to them.

By reason of the fact that the lamps of the system are connected directly to the armature of the generator, when the same is 15 in operation, the battery 5 is required to supply current to the lights only when the generator is not in operation, or is operating at such a low speed that its voltage is less than the battery voltage. As the lamps are 20 generally in use only when the vehicle is in motion, and as only the side and tail lights are necessary and are ordinarily used when the vehicle is stationary, it is obvious that the amount of work done by the battery is 25 comparatively small, and that, even when the vehicle is stationary, the rate of discharge is comparatively slow. For this reason, it is unnecessary that the battery shall always be in a fully or substantially fully 30 charged condition, and the generator is, accordingly, so designed that the battery will charge at a slow rate, even when the lights are not in use. Since the current supplied to the battery passes through the series field 35 magnet winding 3, and since, when the battery is being charged, the series field magnet winding opposes the shunt field magnet winding 2, the generator will be inherently self regulating and its voltage will vary but 40 slightly with changes in its speed.

The compounding of the generator is preferably so adjusted that the generator voltage is less than that of the battery at the speed at which the centrifugally operated switch 4 is automatically closed, and 45 remains less, but increases, as the generator increases in speed to a value corresponding to something less than the average of normal speed of the vehicle. With this arrangement, the proper rate of charging and discharging of the battery may be provided for with little or no danger of overcharging or 50 exhausting the battery. Since, when the voltage of the generator is less than the 55 voltage of the battery, current traverses the series field magnet winding 3 in such direction that the said winding supplements the shunt field magnet winding, it will be seen that the arrangement is such that there is 60 a tendency to increase the voltage of the generator under this condition over a value which it would otherwise assume.

While the invention has been described as useful in connection with engine-driven 65 vehicles, it will be understood that it may

be employed without departing from the spirit of the invention wherever it may be found useful and applicable, and that many modifications in the circuit arrangements may be made within its scope. 70

I claim as my invention:

1. The combination with a source of current, of a distributing circuit supplied from said source, translating devices of different capacities, means for connecting the one or the other of the said devices to the distributing circuit, a resistor that is connected in series with the device of low capacity when the same is connected to the distributing circuit, and means for shunting said resistor 80 when all of said devices are connected to said circuit. 75

2. The combination with a source of current, of a distributing circuit supplied from the source, translating devices of different 85 capacities, means for connecting the one or the other of the said devices to the distributing circuit, and a resistor that is connected in series with the device of low capacity when the same is connected to the distributing 90 circuit. 90

3. A lighting system for a vehicle comprising a source of current, a distributing circuit supplied from said source, head, side and tail lights for the vehicle, means for 95 connecting the head and tail lights to the distributing circuit, means for connecting the side and tail lights to the distributing circuit, and a resistor in series with the latter means. 100

4. The combination with a source of electromotive force, of a distributing circuit supplied from said source of electromotive force, translating devices of different capacities, a resistor, and means for connecting said resistor in series with the device of low capacity when the same is connected to the distributing circuit, and means for shunting said resistor when the device of high capacity is connected in circuit with the device 110 of low capacity. 105

5. In a vehicle lighting system, the combination with a source of electromotive force, of a distributing circuit supplied by said source of electromotive force, head, side and tail lights for said vehicle, means for 115 connecting the head and tail lights to the distributing circuit, means for connecting the side and tail lights to the distributing circuit, a resistor in series with the latter 120 means, and means for shunting said resistor. 120

6. In a lighting system for a vehicle, the combination with a source of electromotive force, of a distributing circuit supplied thereby, head, side and tail lights for said vehicle, means for connecting said head and tail lights to said circuit, means for connecting said side and tail lights to said circuit, a resistor in series with the latter 125 means, and means for shunting said resistor 130

when all of said lights are connected to said circuit.

7. In a lighting system for a vehicle, the combination with a source of electromotive force, of a distributing circuit, head, side and tail lights for said vehicles, a resistor, a switch for connecting the side and tail lights of said vehicle to said circuit in series with said resistor, and a second switch for

connecting the head and tail lights to said circuit and for shunting said resistor.

In testimony whereof, I have hereunto subscribed my name this 23rd day of Dec., 1911.

FRANK CONRAD.
